UNITED STATES PATENT OFFICE.

JAMES SPEAKMAN CLAY, OF RACINE, WISCONSIN, ASSIGNOR TO FREEMAN MFG. CO., OF RACINE, WISCONSIN, A CORPORATION OF WISCONSIN.

TURNTABLE.

Application filed August 7, 1925. Serial No. 48,729.

To all whom it may concern:

Be it known that I, JAMES SPEAKMAN CLAY, a citizen of the United States, and resident of Racine, in the county of Racine and State of Wisconsin, have invented certain new and useful Improvements in Turntables; and I do hereby declare that the following is a full, clear, and exact description thereof.

10 This invention relates to turntables and is particularly directed to a turntable for automobile trucks.

In building operations, it is frequently necessary to conduct the truck loading or dumping and backing in a very limited space. For example, in some States road builders are required to confine their operations to one side of the road only and thus are not allowed sufficient room in which to

20 turn their trucks.

This invention is designed to provide turntables for trucks which will permit the use of trucks in a very limited space, which is reversible and is adapted to receive the 25 truck from either end, which is easily operated by one man to quickly turn a heavily loaded truck, and which is of extremely rugged, and relatively simple construction, and is not likely to be damaged even under 30 the severe use to which these devices will be put.

Further objects are to provide a turntable which is equipped with a pair of structural steel runways which are tiltable and are carried in unloaded condition upon 35 spring pressed caps located substantially centrally of the runways which permit easy tilting thereof, and which, when loaded, are carried by strong transverse beams spaced 40 a material distance apart to thus give a wide range for centering.

Further objects are to provide a turntable which is equipped with friction latches to hold the runways temporarily in tilted position, and which is so constructed that a truck may be driven upon the runway, balancing feet being provided to aid in the initial balancing, and which, when the truck is driven from the runways, the friction 45 latches will retain the runways in a tilting position for the next truck.

An embodiment of the invention is shown in the accompanying drawings, in which:—

50 Figure 1 is a side elevation of the turntable.

Figure 2 is a plan view thereof.

Figure 3 is an enlarged transverse sectional view.

Figure 4 is a sectional view taken on the line 4—4 of Figure 3 with the corresponding runway omitted.

Referring to the drawings, it will be seen that a pair of runways 1 are provided and are constructed of structural steel. These runways are joined at intervals by means of transverse channel iron bracing members 2 and are preferably flared at their ends, as shown in Figure 2. These runways may be constructed of angle irons 3 positioned at opposite sides and joined by a sheet steel 65 floor 4. Preferably, the channel irons 3 are reinforced by upper channel irons 5 which are securely riveted thereto, as shown in Figure 3.

The runways are supported by a base 75 member indicated generally by the reference character 6 and mechanism is interposed between the base member and the runways to permit rotary and tilting motion of the runways even when they support a heavily 80 loaded truck, such mechanism being herein-after described in detail. The base member consists of a base plate 7 of rectangular contour and preferably provided with upturned ends 8, as shown in Figure 2, to permit 85 ready sliding of the base members along the ground so as to permit dragging of the turntable into the position desired. The base plate 7 has a channel iron 9 riveted thereto along each of its side edges, as shown 90 most clearly in Figure 3, and is provided with inwardly spaced angle irons 10 paralleling the channel irons 9, as shown in Figure 3. The ends of the base, as shown in Figure 2, are provided with reinforcing channel irons 11 spaced inwardly from the upturned portions 8, such upturned ends being 95 preferably braced by means of the members 12, as shown in Figure 2. Between the angle irons 10, a cup-shaped raceway 13 is 100 provided, as shown most clearly in Figure 3 and this cup-shaped raceway has its upturned flange riveted to the angle irons 10. The intermediate portion of the race or cup-shaped member 13 is riveted to the base 105 plate 7. Preferably, a strengthening plate 14 is interposed, as shown in Figure 3.

Within the outer raceway, an inner raceway 15 is positioned and is similarly formed cup-shaped. Between these members a 110

double row of balls 16 are positioned and carried by a suitable spacing ring, as shown in Figure 3, grooves being provided in the members 13 and 15 forming tracks for the 5 balls.

A pair of heavy supporting beams 17 extend transversely of the inner member 15 and are riveted thereto. The inner member 15, as shown in Figure 3, is preferably provided with a circular upper flanged member 18 in order to strengthen and reinforce it, and the beams 17 are directly secured to the flange of this member, as shown in Figure 3, thus giving a very rigid attachment 10 between these beams and the member 15. An I-beam 19 (see Figures 2 and 3,) is positioned within the member 15 and is attached to the beams 17. This I-beam has its central web expanded at its center portion to receive the center pin or bolt 20 of 15 the turntable, as shown in Figure 3. Obviously, if desired, two of these bolts may be provided.

The bolt 20 extends through the I-beam 25 19 and is screwed into a bearing plate 21 at its lower end. This bearing plate contacts with a bearing plate 22 carried by the member 13 and preferably a retaining member 23 provided with an inwardly projecting 30 flange is also carried by the member 13 and overhangs a correspondingly contoured portion of the plate 21 thus preventing separation of the parts, this construction being shown in Figure 3. The plates 21 and 22 35 are preferably of steel and brass.

The transverse beams 17 are of I-beam section and are relatively deep at their central portions. They are provided with integral outwardly projecting ends 24 which 40 are positioned beneath the runways 1, as shown in Figures 3 and 4. The runways are normally held out of contact with the arms 24 of the space transverse beams when the runways are unloaded. This is accomplished by means of a pair of spring chairs 45 carried between the transverse beams 17, as shown in Figures 3 and 4.

The construction of these spring chairs is shown most clearly in Figure 4 from 50 which it will be seen that a short cross channel-shaped member or beam 25 rests upon the flanges of the transverse beams 17 and have their ends riveted to the webs of such beams. These members are each provided 55 with a pair of side flanges 26 which are joined by means of transverse intermediate flanges 27 to define a rectangular open top compartment. Preferably four upwardly projecting lugs 28 are formed integrally 60 with the members 25 and receive the lower ends of compression springs 29. The upper ends of compression springs are received by tapered pins 30 formed integrally with the caps 31, such caps being provided with an 65 upwardly extending pointed portion 32.

These caps 31 support the runways when they are unloaded. This is preferably accomplished by providing recesses in the angle irons 3 of the runways, as shown in Figure 3, which receive the pointed portions 70 32 of these caps. These points of support are centrally of the longitudinal dimensions of the runways so that they are substantially perfectly balanced on these spring chairs.

It is to be noted in Figure 3 that the runways have been shown in their depressed position as when loaded while in the imaginary line in Figure 4 the runways have been indicated as unloaded.

It is to be noted from Figure 4 that the 80 outwardly projecting ends 24 of the transverse beams 17 have their outer upper surfaces rounded, as indicated at 24' so as to provide a rounded bearing surface for the 85 rocking runways.

As shown in Figure 1, spring friction latches are carried on the lower side of the runways 1 and each preferably consists of a plunger having a tapered front end 33 which is supported by means of links 34. 90 Its rear end is guided by a bracket 35 and a compression spring 36 is positioned between the bracket and the head of the plunger to urge the plungers towards each other, as shown in Figure 1. These plungers 95 contact with the ends 24 of the transverse beams 17, such ends being preferably made with a solid or smooth portion 37 against which the friction latches bear. If desired, this flat surface may obviously be formed 100 by inserting a block of material between the upper and lower flanges of the end portions 24, although preferably the portions 37 are integral with the portions 24.

In order to facilitate dragging of the turntable into place, a pair of eyes 38 are securely attached to the end channel irons 11 of the base, as shown in Figure 2, to receive the hook of a chain, for instance.

A pair of transverse shafts 39 are journaled on the under side of the runways and are provided with balancing feet 40 which are normally out of contact with the ground even when in their downwardly extended position, as shown on the left hand side of Figure 1. These balancing feet are rocked by means of short levers 41 secured to the shafts 39 and connected by means of rods 42 with levers 43 pivoted at the ends of the runway opposite the corresponding feet, 110 suitable stops 44 being provided for the levers 43.

In operating the reversible turntable, it is placed a short distance from the point where the building material is required, for instance on one side of a road if the turntable is used for roadway constructions. A loaded truck approaches a turntable and mounts the runways. As the driver passes the nearest lever 43 he rocks it forwardly, as 115 120 125 130

shown on the right hand side of Figure 1, thus positioning the most remote balancing feet 40 in their downwardly extending position as shown on the left hand side of Figure 1, it being assumed in such figure that the truck is approaching on the right hand side. The truck mounting the runways depresses the springs 29 and the runways 1 into contact with the cross arms. The truck 5 travels forward until the center of gravity of the load passes the center of the turntable at which time the runways tilt down to a horizontal position. The truck is stopped while in this position and the driver 10 mounts and raising the balancing feet turns the loaded turntable until the truck is facing in the opposite direction. The truck is then backed off the turntable to the point where the load is dumped. The empty 15 truck is then driven back over the turntable leaving the runways down in position to receive the next loaded truck. In these operations it is not necessary for the truck at any time to use any part of the highway except the side occupied by the turntable.

It is obvious that the turntable may be used in other capacities and ways than that which is described in detail, but it is believed from this description that the use of the 20 turntable will be fully appreciated.

It will be seen that a turntable has been provided which will receive and turn loaded trucks, which may be easily operated, and which is reversible.

Although the invention has been described in considerable detail, it is to be understood that the invention may be variously embodied and is, therefore, to be limited only as claimed.

I claim:

1. A turntable comprising a supporting base, a pair of transverse beams positioned above said base, rotatable means interposed between said beams and base for permitting 45 relative turning motion of said beams with reference to said base, a pair of longitudinally extending runways for the reception of the wheels of a truck, and yielding means for normally supporting said runways out 50 of contact with said transverse beams.

2. A turntable comprising a supporting base, a pair of transverse beams positioned above said base, rotatable means interposed between said beams and base for permitting 55 relative turning motion of said beams with reference to said base, a pair of longitudinally extending runways for the reception of the wheels of a truck, yielding means for normally supporting said runways out of contact with said transverse beams.

contact with said transverse beams, and 60 friction latches carried by said runways and adapted to yieldingly retain said runways in a tilted position.

3. A turntable for trucks comprising a base, a pair of transverse beams positioned above said base, a ball bearing interposed between said beams and base and permitting said beams to turn with reference to said base, a pair of spring pressed caps positioned between said beams, a pair of runways normally supported by said caps and extending across said beams, said runways being adapted to receive the wheels of a truck, whereby said runways are depressed against the action of said springs and are supported by said transverse beams.

4. A turntable for trucks comprising a base, a pair of transverse beams positioned above said base, a ball bearing interposed between said beams and base and permitting said beams to turn with reference to said base, a pair of spring pressed caps positioned between said beams, a pair of runways normally supported by said caps and extending across said beams, said runways being adapted to receive the wheels of a truck, whereby said runways are depressed against the action of said springs and are supported by said transverse beams, and a pair of rocking balancing feet carried adjacent the outer ends of said runway and adapted to be temporarily rocked downwardly.

5. A turntable for trucks comprising a base, a pair of transverse beams positioned above said base, a ball bearing interposed between said beams and base and permitting said beams to turn with reference to said base, a pair of spring pressed caps positioned between said beams, a pair of runways normally supported by said caps and extending across said beams, said runways being adapted to receive the wheels of a truck, whereby said runways are depressed against the action of said springs and are supported by said transverse beams, a pair of transverse shafts carried beneath the runways adjacent their outer ends, balancing feet carried by said shafts, a crank arm connected to each of said shafts, a lever mounted adjacent each end of said runways and on opposite sides thereof, and rods connecting said levers and said crank arm.

In testimony that I claim the foregoing I have hereunto set my hand at Racine, in the county of Racine and State of Wisconsin.

JAMES SPEAKMAN CLAY.
